Primary Examiner — Paula Allen Greene(74) *Attorney, Agent, or Firm* — Howson & Howson LLP(57) **CLAIM**

The ornamental design for a computer casing, as shown and described.

DESCRIPTION

1. Computer casing
- 1.1 Front
- 1.2 Side Perspective
- 1.3 Side Perspective
- 1.4 Back
- 1.5 Side Perspective
- 1.6 Top
